(57) **CLAIM**

The ornamental design for pair of side structures for furniture, as shown and described.

DESCRIPTION

FIG. 1 is a right hand perspective view of a first embodiment of a pair of side structures for furniture embodying the design,

FIG. 2 is an enlarged view of the upper right-hand corner of FIG. 1,

FIG. 3 is a front view of the first embodiment,

FIG. 4 is a right side view of the first embodiment,

FIG. 5 is a front view of a second embodiment of a pair of side structures for furniture embodying the design; and,

FIG. 6 is a front view of a third embodiment of a pair of side structures for furniture embodying the design.

The broken lines are for environmental purposes only and form no part of the claimed design.
